UNITED STATES PATENT OFFICE.

IRA LENNOX, OF GRAND JUNCTION, COLORADO.

COLLAPSIBLE WINDOW SHUTTER OR SHIELD.

Application filed July 16, 1927. Serial No. 206,205.

This invention relates to window shutters or shields, and the general object of the invention is to provide a window shutter or shield which, while permitting full ventilation of a room, will prevent burglars from entering the room through the window and will prevent anyone looking into the room from the outside.

A further object is to provide a construction of this character which will fold up into a small space, which may be readily handled and shifted into or out of position, and which is adapted to be raised to different heights and held at these different heights.

15 A still further object is to provide a device of this character including a plurality of V-shaped leaves or members which are flexibly connected to each other so that they may be held in spaced relation when the shutter or shield is expanded or raised or folded into nesting relation when the shutter or shield is contracted.

Another object is to provide means whereby the lower end of the shutter may be detachably locked in place in such position that the locks cannot be released by anyone exterior to the building.

Still another object is to provide latches which detachably support the upper end of 20 the shutter or shield.

Still another object is to provide a shield or shutter of this character which may be used as an awning in the sense that it will permit the entrance of air but will prevent 25 the entrance of the sun when the shield is raised.

Other objects have to do with the details of construction and arrangement of parts as will be more fully understood hereinafter.

40 My invention is illustrated in the accompanying drawings, wherein:

Figure 1 is a face view of a shutter constructed in accordance with my invention;

Figure 2 is a vertical sectional view 45 through a series of these shutters, the section being taken longitudinally;

Figure 3 is a like view to Figure 2 but showing the leaves closed;

Figure 4 is a fragmentary longitudinal section on a horizontal plane through the lowermost leaf, a portion of the window frame, and the locking bolt;

Figure 5 is a section on the line 5—5 of Figure 2;

55 Figure 6 is a section on the line 6—6 of Figure 3;

Figure 7 is a section on the line 7—7 of Figure 2;

Figure 8 is a section on the line 8—8 of 60 Figure 7;

Figure 9 is a face view of one of the guides.

Referring to the drawings, 10 designates a window casing of any suitable character and including the sill 11, the jambs 12, and the lintel 13. The jambs 12 are formed with guides 65 14 which may be made of metal, wood or any other suitable material but, as illustrated, these guides are formed of a hollow shell 16 of metal with a wooden core disposed within the guides. Each guide is formed with the 70 outwardly projecting rib 17 extending from top to bottom of the guide, and the lower end of each guide rests upon the sill 11. The guides are formed at their upper ends with two openings 18 constituting keepers, these 75 openings being disposed one on each side of the rib 14.

Adjacent the middle of the guide there is also formed two openings 18 or keepers 80 which are disposed one on each side of the rib. At the lower end of each guide there is a double opening or keeper, designated 19, disposed on each side of the rib 14. This opening differs slightly from the openings 18, as the openings 19 in each guide are rectangular in form, while preferably the openings 18 are somewhat semi-circular. Operating 85 between these guides are a plurality of V-shaped leaves 21 constituting shutter or shield sections.

90 While I have illustrated a certain number of leaves, it will be understood that the number of leaves used in a window may be more or less, depending upon the height of the window. Each leaf, except the top leaf, is 95 formed of a single piece of sheet metal bent to provide a bead 22 and the downwardly diverging wings 23. Each bead at its ends is longitudinally slotted at 24, these slots being for the reception of the guide ribs 14. Disposed within the bead of each leaf, except the topmost leaf and the lowermost leaf, are two pairs of longitudinally slotted rod sections 25. Each of these rod sections is longitudinally slotted, as at 26, from one end toward the 100 other, and these slotted ends of each pair of rod sections confront each other. These rod sections are oscillatable within the bead 22. 105

The outermost rod sections are riveted or otherwise attached to the beads but the innermost rod sections 25 have a limited sliding movement. Extending through a slot adja- 110

cent the ends of each bead are the links 27 which are pivotally connected to the lowermost member or section 25 by means of a rivet 28 or other pivoting means, and these 5 links 27 extend upward and inward and extend into the slot of the rod section 25^a of the leaf above to which they are pivotally connected by pivots 28. The slots in these pintles 25 and 25^a permit the links to fold up into 10 nearly parallel relation to the bead so that the several leaves may nest one within the other, as shown in Figure 3. When, however, the uppermost leaf is raised and the other leaves suspended thereby, the links 27 will swing 15 inward toward each other to the position shown in Figure 2 and the leaves will be held one immediately below the other in spaced relation.

The leaves or shield sections are of such 20 depth and the links are of such length that the upper edge of one leaf or shield section can never drop below the lower edges of the next adjacent shield section or leaf, and thus while air may pass between these leaf sections, as 25 shown in Figure 5, a complete obstruction will be provided against anyone looking into the room, as any straight view will be obstructed.

As shown in Figure 2, each of the leaf sections from top to bottom is provided at the 30 ends of each wing with the outwardly projecting lugs 29 which engage against the forward and rear faces of the guide 14 so that the leaf sections are held from any inward 35 or outward swinging movement. The pintles 25^a being oscillatably mounted within the beads secure such flexibility in the connected and interlinked leaves or shield sections that there is no danger of the leaves sticking or 40 becoming jammed.

All of the leaf sections from top to bottom are alike, except the top and bottom sections. These slightly differ from the intermediate sections in a manner which will now be stated. 45 The lowermost section 30, as shown in Figure 6, has the bead 22 and the wings 23, but in addition the wings 23 are intersected by a transverse partition plate 31 which, between the bead 22 and the partition plate, defines 50 an irregularly sided tube. Disposed within this tube is a coiled compression spring 32 which bears at its ends against two shiftable latch bolts 33. Each of these latch bolts at its extremity is longitudinally slotted, as at 34, 55 and rearward of the end of the latch bolt the under face of the latch bolt at its ends is cut away, as at 35, so as to leave two separated bills 36. The slot 34 is adapted to accommodate the rib 14 and the bills 36 are 60 adapted to engage within the lowermost openings 19 so as to hold the shield in a lowered position. These bolts 33 are urged outward by the spring 32, and passing through a slot 37 formed in the partition 31 is the shank of 65 an eye or finger piece 38. By pulling inward

on these finger pieces 38, both bolts may be retracted so as to disengage the lower end of the shield from the keepers 19 and permit the shield to be raised. So long as these keepers 19 are engaged with the guides 14 through 70 the openings 19, it is impossible for the lower end of the shield to be raised.

The wing 23 on the inner side of this lower leaf is cut away at 39 so as to permit the fingers to be inserted in engagement with the handles 38, but the outer wing is not so cut away so that no access can be had to these handles from the exterior of the window. The uppermost leaf 22 is also approximately V-shaped but is formed to provide two oppositely disposed beads 40 separated from each other by an intermediate, upwardly curved, longitudinally extended portion 41 which is longitudinally slotted at its ends, as at 42. Disposed within the medially disposed bead 85 43 which corresponds to the bead 22 are the pintles 44, these pintles being connected by a longitudinally extending link 45 which is pivoted at its ends in slots 46. Links 47 which correspond to the links 27 extend from 90 the pinte members 44 downward and outward to the pinte members 25 of the subjacent leaf. The pintles 44 are longitudinally slidable within the bead or tube 43, the entire tube being open for this purpose from one 95 end to the other.

Disposed within the ends of the beads 40 are the twin latch bolts 48, these bolts being longitudinally slotted, as at 49, and being connected to each other by the outwardly turned flanges 100 50 of eyes 51, these eyes extending up through the slots 42. Springs 52 act to force these bolts outward and the extremities of the bolts are cut away upon their under faces, as at 53, so that the ends of the bolts constitute 105 hooks which are engageable in the apertures 18. After the bolts have been put in place, a plate 54 having therein a longitudinal slot 55 and a longitudinal slot 56 is welded in place over the slot 42, thus preventing any 110 removal of the bolts. Welded or otherwise attached to the uppermost leaf between the slots 55 are a series of connected eyes 57.

It will be understood that a plurality of eyes 51 may be connected to each pair of bolts 115 48, if desired and that any number of eyes 57 may be disposed between the latch eyes 51. Preferably the leaf next to the topmost leaf and any desired number of leaves below this are formed with an intermediate lug 58 that 120 keeps the leaves from spreading or letting the parts bind.

It will be seen that this invention may be applied to windows of many different characters. The uppermost leaf may be disengaged 125 from the keepers 18 and lowered half way down the window or lowered so that all of the leaves will rest one on top of the other upon the sill of the window. Obviously the jambs of the window may be formed with more 130

openings 18 than are illustrated so that this flexible shutter or shield may be raised up to any height required. When raised to its full height, the uppermost shield will come, 5 under ordinary circumstances, about two feet from the lintel of the window, too high for any burglar to reach or anyone to look over. The lowermost leaf may merely rest upon the bottom of the window sill if desired and not have any latches for holding it in place, but 10 preferably it will have such a latch, as I have illustrated, as thus this shutter is rendered burglar-proof, as no burglar or other person can raise the lower end of the lower leaf from 15 the outside. When the shutter is expanded and the uppermost leaf is engaged with the openings 18, the leaves cannot be either shifted up or down but will be held firmly in place, as illustrated in Figure 1, so that air 20 may pass through into the room without, however, permitting anyone looking through the shutter into the room.

It will be seen from Figure 5 that the separate leaves nest very closely due to the fact 25 that each leaf is rounded at its upper end so that the beads may set one upon another. Thus each leaf only takes a space of about $\frac{3}{8}$ " when folded. While I have illustrated a 30 shutter or shield which is moved upward from the sill of the window, I do not wish to be limited to this as it is obvious that this shutter or shield could be made to disappear down through the window sill with the top shield resting upon the window sill. The shutter 35 or shield could then be lifted, when desired, through the window sill and lifted up to any extent required. The upper catch shown in Figure 8 is larger than the lower catch so that 40 it will not interfere with the other parts of the curtain and it is somewhat wider than the lower catch so that it will not catch in the holes into which the lower catch is supposed to engage.

While I have illustrated certain details of 45 construction and arrangement of parts, I do not wish to be limited to this, as obviously this may be changed in many ways without departing from the spirit of the invention as defined in the appended claims.

50 I claim:—

1. The combination with a window frame, 55 of a collapsible shutter comprising a plurality of inverted V-shaped leaves, links pivotally connecting the leaves with each other, each link having sliding engagement with one 60 of said leaves, the window frame having guides with which said leaves engage, the ends of the leaves having sliding engagement with the guides, means for supporting the uppermost leaf at any one of a plurality of elevations on the window casing.

2. The combination with a window frame 65 having vertically disposed guides on its jambs, of a collapsible shutter comprising a plurality of inverted V-shaped leaves, each

of said leaves being formed to provide two wings and a hollow bead at the crest of the leaf, pintles disposed in said hollow beads, links connecting the pintles of one leaf with the pintles of the next adjacent leaf, the links 70 being pivotally connected to the pintles, and means for locking the uppermost leaf in any one of a plurality of vertically adjusted positions upon the guides.

3. The combination with a window frame 75 having vertically disposed guides on its jambs, of a collapsible shutter comprising a plurality of inverted V-shaped leaves, each of said leaves being formed to provide two wings and a hollow bead at the crest of the 80 leaf, pintles disposed in said hollow beads, links connecting the pintles of one leaf with the pintles of the next adjacent leaf, the links being pivotally connected to the pintles, and spring actuated bolts mounted upon the 85 uppermost leaf, the guides having a plurality of keepers with which said bolts are adapted to engage at different elevations.

4. The combination with a window frame 90 having vertically disposed guides on its jambs, of a collapsible shutter comprising a plurality of inverted V-shaped leaves, each of said leaves being formed to provide two wings and a hollow bead at the crest of the leaf, pintles disposed in said hollow beads, links 95 connecting the pintles of one leaf with the pintles of the next adjacent leaf, the links being pivotally connected to the pintles, and spring actuated bolts mounted upon the uppermost leaf, the guides having a plurality of 100 keepers with which said bolts are adapted to engage at different elevations, the lowermost leaf having spring actuated bolts at its ends and the guides having keepers at their lower 105 ends for engagement with said bolts, the inside wing of the lowermost leaf being cut away and the bolts having operating handles disposed inside of said cut-away portion of the leaf whereby the bolts may be retracted from inside the window.

5. The combination with a window frame 110 having vertically extending guides upon the inside faces of its jambs, each guide being formed with a medial rib, of a collapsible shutter comprising a plurality of inverted 115 V-shaped leaves, each leaf comprising two upwardly convergent wings and a bead, the bead being slotted at its ends to receive said ribs and the wings being extended adjacent their lower margins to embrace the guides, 120 longitudinally slotted pintles having limited sliding movement within said beads, downwardly divergent links pivoted within the slots of the pintles and flexibly connecting one of the leaves with the next adjacent leaf to thus permit the leaves to be shifted downward into nested position one within the other or shifted upward to suspend the leaves from the topmost leaf, said links limiting the movement of the leaves away from each other to a 125 130

position where the lower margins of the wings of one leaf are below the crest of the next adjacent leaf, and means for locking the uppermost leaf in any one of a plurality of vertically adjusted positions upon the window casing.

6. The combination with a window frame, of a collapsible shutter comprising a plurality of inverted V-shaped leaves, links pivotally connected at their ends to adjacent leaves at the apices of said leaves, the window frame having guides with which said leaves have sliding engagement, and means for locking the uppermost leaf at any one of a plurality of elevations on the window casing.

10 7. The combination with a window frame, of a collapsible shutter comprising a plurality of inverted V-shaped leaves, a pair of pintles disposed in sliding engagement in the apex of each leaf and having limited longitudinal movement with relation to the leaf, the pintles being slotted, and links pivoted within the slots of each pair of pintles and extending angularly downward and pivoted in the slots of the pintles below whereby to 20 flexibly connect the leaves and permit said leaves to be shifted downward into nested position or lifted into an extended position.

8. The combination with a window frame, of a collapsible shutter comprising a plurality of inverted V-shaped leaves, each leaf having downwardly diverging wings and a bead forming the crest of the leaf, a plurality of pintles disposed within each of the beads and having limited longitudinal movement therein, the pintles being slotted, and links pivoted within the slots of each pair of pintles and extending angularly downward and pivoted in the slots of the pintles below whereby to 30 flexibly connect the leaves and permit the leaves to be shifted downward into nested position or lifted into an extended position.

40 9. The combination with a window frame

having vertical guides in the jamb thereof, of a collapsible shutter comprising a plurality of inverted V-shaped leaves disposed one above the other and slotted and having sliding engagement with the guides, links pivotally connecting the leaves to each other, each link having engagement with one of the leaves for sliding movement longitudinally of the leaf and having pivotal engagement with the same leaf, said links permitting the leaves to be nested one within the other but preventing the leaves from being shifted apart to a degree where the leaves will not overlap, and bolts carried upon the uppermost leaf, the guides being formed with apertures or keepers with which said bolts are adapted to engage.

10. The combination with a window frame 60 having vertical guides in the jamb thereof, of a collapsible shutter comprising a plurality of inverted V-shaped leaves disposed one above the other and slotted to have sliding engagement with the guides, links pivotally connecting the leaves to each other, each link having sliding engagement with one of the leaves longitudinally of the leaf, said links permitting the leaves to be nested one within the other but preventing the leaves from being shifted apart to a degree where the leaves will not overlap, and bolts carried upon the uppermost leaf, the guides being formed with apertures or keepers through which said bolts are adapted to engage, the lowermost leaf 70 having bolts and the guide having keepers with which the bolts are adapted to engage, the lowermost leaf being cut away upon its inner face to prevent the operation of the bolts from inside the window.

In testimony whereof I hereunto affix my signature.

IRA LENNOX.
